UNITED STATES PATENT OFFICE.

GEORGE L. DAMON, OF PITTSBURG, PENNSYLVANIA.

MOUNTING FOR HEAVY VAULT-DOORS.

No. 901,425.

Specification of Letters Patent.

Patented Oct. 20, 1908.

Application filed September 16, 1907. Serial No. 393,181.

To all whom it may concern:

Be it known that I, GEORGE L. DAMON, a citizen of the United States, and a resident of Pittsburgh, in the county of Allegheny and State of Pennsylvania, have invented a certain new and useful Mounting for Heavy Vault-Doors, of which the following is a specification.

My invention relates to means by which a heavy fire and burglar-proof door may be mounted so as to swing out of the way to open a vault or other like inclosure and be swung back and be presented with exactness in proper position to enter the opening which the door is intended to close and for which it is constructed with such accuracy as to form therewith a closure that is tight and proof against the introduction of gaseous liquid or other explosives.

20 In the construction of doors for heavy burglar and fire-proof vaults, which doors are now made of excessive weight, it is customary to design the opening and its door with circular section and with tapered and offset walls so that the door may be pressed firmly to a seat in the opening, and the fit is made with such exactness as to pass a test, which consists in placing the member containing the opening, with the door therein, 25 in horizontal position and applying water or other liquid to the surface around the joint and ascertaining whether any portion of the liquid will enter between the parts. This accuracy of fit is obtained by grinding the parts after the manner of fitting the stopper to a bottle. As a further security, suitable felt or other packing material is located between the offset faces for the purpose of further insuring against the passage of explosives. For the purpose of seating these doors, which also involves compressing the packing, they are usually provided with compressor systems comprising a number of cam-like latches distributed at suitable 30 points around the circumference of the door, with their keepers on the door frame and having their shafts extending to the center of the door and there brought under control of a means by which they may be manually 35 rotated with multiplication of power. It has been found with doors of this character that a very slight yield at the pivot end of the hinge which may result from wear or other disarrangement of the carefully de-

signed ball bearings, and with the amplifying of the disarrangement thus produced, at the outer end of the hinge, which receives the door at its vertical diameter, the door begins to drag over the bottom wall of its opening, and prevents a proper seating and therefore leaves a crack or space at top, which becomes aggravated as the dragging causes wear on the contacting parts of the door and jamb, thus defeating the object of the expensive method of fitting the door referred to. With such disarrangement, seating of the door involves lifting it by forcing it up the inclined surface upon which it is resting. Inasmuch as the compressor systems ordinarily used will exert a pressure equal only to about one-fourth the weight of the door, which varies from twelve to seventeen tons, it becomes a physical impossibility to properly seat the door and the consideration for the expense that has been incurred is thus defeated in a comparatively short time after the structure is erected.

My invention has for its object to provide means for rendering ineffective the unavoidable settling in the hinges of doors of the character described and it consists primarily in so balancing the weight of the door that it is a comparatively easy matter to seat the door, notwithstanding any change in the adjustment of any of the supporting parts; this being accomplished by the application of comparatively little work.

More specifically, my invention consists in embodying at a suitable point or points between the door and the vault structure in relation to which it is movably supported to swing, elastic means through which the weight of the door is either directly or indirectly sustained, of such strength that the weight of the door is yieldingly sustained either in position to enter its opening or at such close proximity thereto as will permit the door being forced to its seat by sliding over that portion of the beveled face of the opening which happens to be impinged (determined by the eccentricity of the door to the opening); the said yielding sustaining means continuing to bear the greater portion of the weight of the door, even after contact of the beveled faces so that the application of power necessary to seat the door is comparatively small and well within the capacity of the compressor system; so that

the latter device may be used for its intended purposes of bringing the entire circumference of the door into intimate explosive tight contact with the surrounding jamb and 5 imposing the compression on the packing, which is necessarily incident to such a seating when the structure is properly designed.

More specifically, my invention embodies a resilient support or supports which will 10 expand and continue to sustain the weight of the door if the door impinges one part of its jamb, or which may be compressed, while still sustaining the door, when the door impinges an opposite point in its jamb, and 15 this expansion or compression being attainable with slight application of power applied to the spring either through the cam action of the impinging tapered surfaces or through a similar cam action of special rubbing surfaces provided respectively on the 20 door and its jamb.

One embodiment of my invention is shown in the accompanying drawings, in which

Figure 1 is a front elevation of a portion 25 of a vault and its door in which my invention is embodied. Fig. 2 is a section in the plane of the vertical diameter of the door shown in Fig. 1. Fig. 3 is a sectional detail view of one of the connections between the 30 hinge and the door, in which the resilient sustaining means is preferably located. Fig. 4 is a plan view of parts shown in Fig. 3. Fig. 5 is a detail view of an automatic centering device, the coöperating members of 35 which are applied respectively to the door and the door frame at the point in the circumference where impingement or drag would take place.

Referring more particularly to Figs. 1 and 40 2, A represents a portion of the vestibule or other structure having a door B fitted to an opening therein by the usual beveled and offset surfaces and supported by a Crane hinge C having pintle bearings D on the 45 fixed part of the structure and swivel connections E with the door in the line of its vertical diameter. These parts may be of known construction and they are preferably provided with equally well known compres- 50 sion system F—G.

The door B when constructed for a large fire and burglar-proof vault for banking or safe-deposit purposes, will weigh from twelve (12) to seventeen (17) tons, whereas 55 the compression system F—G provided for the purpose of seating the door is incapable of exerting a pressure corresponding to more than one fourth of such a load; hence any sagging of the door or yield in its support- 60 ing connections, will make it impracticable to secure a satisfactory closure. To overcome the effect of such sagging, and for the purpose of embodying the principle of my invention already outlined, I provide a yield- 65 ing sustaining connection, preferably in the

form of a coil spring 1 located in a position to sustain the door in the direction in which the tendency to sag is ordinarily exerted. This will generally be in a vertical direction and downward, for which reason I prefer to locate this spring around the swivel pin 2 of the connection E between the Crane hinge and the door, both at top and bottom, the pin 2 being provided with a shoulder 3 to sustain the spring and the housing 4 of the connection E being enlarged to accommodate the spring and receive its upper end. The leaf 5 of the connection E, which is bolted directly to the door thus becomes the means of supporting the door on the hinge through 80 medium of the spring, the relation of the parts being sustained laterally by the bearings of the housing 4 on the upper end of the pin and on its shoulder and the parts being sustained against vertical displacement and the initial compression of the spring being established by means of a nut 6 held to its adjustment by lock nut 7. 8 represents a bushing interposed between the 85 pin 2 and the spring 1.

While the compression of the spring and consequently the vertical adjustment of the door relatively to its supporting hinge may be secured through the nut 6, said nut is primarily designed to merely bring the housing 4 in proper relation to the pin 2 and the adjustment referred to is more satisfactorily secured by raising or lowering the seat of the pin 2 in the bore formed in the leaf of the Crane hinge, to receive said pin, for 95 which purpose said pin is sustained by an adjusting screw 10 that may be turned up or down by its protruding lower end 11, faced to receive a tool, and locked to any adjustment by the jam nut 12. The turning movement which takes place in the swivel connection E is preferably provided for between the pin 2 and the hinge leaf, and the friction thereof is reduced by a ball bearing 9 comprising upper and lower disks 110 with interposed balls.

As stated, the particular construction of swivel connection E is provided at both top and bottom of the door but description of one of said connections will suffice for both. 115

If desired, the yielding connection or sustaining means might be located at the pintle end of the Crane hinge, either at top or bottom or at both top and bottom of said pintle; or it might be located in a position to yield- 120 ingly sustain the bearings of said pintle in a direction transverse to the axis thereof without departing from the spirit of my invention which contemplates any use of the resilient or yielding medium introduced in 125 such relation to the door as to sustain wholly or mainly the load of the door and reduce the work necessary to force the door into seating relation to its jamb. It is also to be understood that my invention is not limited 130

in its application to a door mounted upon a swinging hinge, for while the swinging hinge has heretofore been the only practicable means of sustaining a heavy door in proper relation to the opening which it is to close, the ease with which a door can be brought into concentric relation from a much greater degree of eccentricity, by the use of my invention, will make it practicable to use other forms of supporting means than hinges, as for instance a vehicle or carriage by which the door is mounted to move first in an axial direction and then in any other direction that will remove it to give access to the inclosure.

My invention would compensate for the yield in the support afforded by such a vehicle where doors mounted in the ordinary way could not be returned to their seats after being once removed by such means.

With a mounting constructed in accordance with my invention as above described, it is obvious that if the door sags into contact with the bottom of the jamb, the springs adjusted to point where they are almost lifting the door will make it an easy matter to center the door and force it to its seat. If, on the other hand, the seat of the spring has been adjusted to such a height that the door is supported a little above its centered position, it is simply a matter of compressing the spring lightly to lower the door into centered position. In either event, the door is yieldingly supported adjacent to its seating position by a resilient sustaining means bearing such relation to the weight of the door as will cause it to automatically adjust the support, under the application of a relatively small seating pressure, while still maintaining its sustaining relation to the door.

I prefer to employ in practice that adjustment of the support which will normally hold the door slightly above its seating center and to cause the automatic adjustment of the support to effect the centering of the door, under the application of the relatively small seating pressure, to take place by further compression of the spring.

Whether the support be adjusted to sustain the door normally above or below its seating position, I prefer to provide means which will relieve the drag or friction between the beveled surfaces until the door is substantially seated and for this purpose I provide a bracket 13 and a pressure foot 14 mounted one on the door and the other on the door jamb (the bracket being preferably on the door jamb) and with an anti-friction roller carried by the pressure foot so that these parts become the means through which the seating pressure applied to the door through the compressor system or otherwise is translated into a centering movement of the door while the yielding supporting means automatically adjusts itself to continue its

support to the door. This portion of my invention therefore comprises coöperating centering means independent of the seating faces of the door and its jamb, mounted respectively on the door and a surrounding portion of the structure at or adjacent to that point in the circumference which is in the direction of eccentricity and impinging during the act of closing the door to cause the door to move to a position concentric with the doorway. One of these coöperating centering members (preferably the bracket) is adjustable in order that it might be set so as to perform its function with accuracy. With the preferred plan of adjusting the spring to support the door slightly above its seating position, these coöperating centering members will be located at the top of the door as shown in the drawings. When located at the top of the door, the member carried by the door may be conveniently constructed as a part of or mounted upon the cap 15 which covers the upper end of the pin 2 and the nuts 6 and 7.

The springs are to be so built that they will yield and continue their supporting relation to the door when the door has been shifted from the point at which it is normally sustained. That is to say, the spring is built with a high coefficient of elasticity, or with such stiffness (determined mainly by its section and the diameter of its coils) relatively to the weight of the door, and of such length, that when the door is supported with its center above the center of the doorway, a relatively small additional load will be required to depress it the distance required to center it, and, conversely, when the door is supported with its center normally below the center of the doorway, only a small loss of lifting power results from the extension of the spring incident to centering the door, hence a relatively small application of lifting force is required to center the door. The loss of lifting power by extension of the compressed spring, or the increased resistance resulting from further compression of a spring already under load is ordinarily determined by the proportion of the distending or compressing movement to the entire length of the spring unloaded.

While I have illustrated and described my invention as applied to a vault door of circular section, I desire it is understood that my invention is by no means limited to use on doors of this particular type but is obviously adapted with equal advantages to doors of other section, such as doors having parallel sides joined by curves or angles to form straight or rounding corners.

Having thus described my invention, what I claim and desire to secure by Letters Patent, is:

1. The combination with a door and a structure in relation to which the door is

movably supported to swing, of a yielding supporting medium interposed between said door and structure, and means for adjusting the position of the supporting medium on 5 said structure.

2. The combination with a doorway and a door, of means for supporting the door in opening and closing relation to the doorway; said door-supporting means comprising a 10 yielding medium by which the entire weight of the door is sustained, and means for adjusting the height of said medium relatively to the doorway.

3. The combination with a doorway and a 15 door, of means for supporting the door in opening and closing relation to the doorway; said means comprising a resilient hinge upon which the door is adapted to turn.

4. In combination with a doorway and a 20 door, of a yielding supporting medium interposed between the door and the doorway; said medium being constructed to automatically adjust itself in its sustaining relation to the door and provided with means for adjusting its position relatively to the doorway.

5. In combination with means for movably supporting a door in relation to a doorway; a yielding medium sustaining the door and 30 continuing its support of the door while permitting the door to shift in its own plane to center it with the doorway, and means for shifting the door to center it.

6. In combination with the means for 35 movably supporting a door in relation to a doorway; a yielding medium sustaining the weight of the door and supporting the door normally above the doorway, and means for forcing the door downwardly to its seat in 40 the doorway.

7. In combination with means for supporting a door in movable relation to its doorway; a yielding sustaining medium interposed in said supporting means which 45 normally supports the door approximately in line with its seated position, and means centering the position of the door relatively to the doorway, independent of the seating faces.

8. In combination with the means for supporting a door in movable relation to its doorway; a yielding medium interposed in 55 said supporting means, through which the entire weight of the door is sustained, when the door is not seated, said means being adjusted to support the door approximately in line with its seating position and yielding to continue its support when the door is shifted to bring it into line with its seating position; means independent of the seating surfaces for deflecting the door into its seating 60 position and a compressor system for forcing the door to its seat.

9. In combination with means supporting 65 a door in movable relation to its doorway; a

spring interposed in the supporting means in position to sustain the weight of the door and provided with means whereby its position may be adjusted vertically.

10. In combination with means for supporting a door in movable relation to its doorway; a pin through which the door has swiveling connection with its supporting means and a compressible spring surrounding 70 said pin and sustaining the weight of 75 said pin and sustaining the weight of the door.

11. In combination with means for supporting a door, in movable relation to its doorway; a pin through which the door has swiveling connection with its supporting 80 means, a compressible spring surrounding said pin and sustaining the weight of the door; and means for adjusting the position of said spring to determine the height at 85 which the door is sustained.

12. In combination with means for supporting a door in movable relation to its doorway; a pin through which the door has swiveling connection with its supporting 90 means, and a compressible spring surrounding 95 said pin and normally sustaining the door above its seating position; said spring being adjustable in position to determine the height at which the door is sustained.

13. In combination with the means for supporting a door in movable relation to its doorway; a yielding sustaining connection in said supporting means comprising a shou- 100 dered pin, a spring resting upon the shoul- 105 der of the pin, and a bearing member carried by the door, receiving the pin and resting upon the spring.

14. In combination with a door, its doorway and means for resiliently mounting the door in relation to its doorway; a centering 105 means independent of the seating faces of the door comprising two contacting members carried respectively by the door and surrounding portion of the doorway.

15. In combination with a door, a doorway and means supporting a door in movable relation to the doorway; a bracket and a presser foot carried respectively by the door and a surrounding portion of the doorway in position to impinge one against the 110 other as the door approaches its seat and cause the door to be centered with the doorway to permit its proper seating.

16. The hereinbefore described centering attachment for doors, comprising a presser 115 foot carrying an anti-friction roller and a bracket provided with a traverse surface; said bracket and presser foot being secured respectively to the door frame and the door in position to cause impingement between 120 the roller and the traverse surface as the door approaches its seat and cause the centering of the door.

17. In combination with a hinged door, its doorway and a compressor system for forc- 130

ing the door to its seat; auxiliary centering means for relieving the work imposed upon the compressor system in centering the door, said means comprising an adjustable resili-
5 ent medium interposed between the door and its hinge.

The foregoing specification signed at Pitts-

burg, Pennsylvania this first day of Febru-
ary, 1907.
